GAS BLAST CIRCUIT BREAKER

Hans Thommen, Baden, Switzerland, assignor to
 Aktiengesellschaft Brown, Boveri & Cie, Baden,
 Switzerland

Application February 7, 1940, Serial No. 317,752
 In Germany November 17, 1938

3 Claims. (Cl. 200—148)

The invention relates to fluid blast circuit breakers and to arc extinguishing means therefor.

The invention has particular reference to a gas blast circuit breaker in which one of the contacts is in the form of a nozzle through which the air under pressure flows from a pressure chamber after opening of the contacts and in which a protective resistance is provided across the breaker contacts, which resistance is switched in by an auxiliary spark gap in parallel with the breaker contacts.

In equipment of the character specified, it has been found that the effectiveness of the auxiliary spark gap in extinguishing the arc resulting from a recovery voltage of steep wave form after the switching arc has been extinguished is improved when the escaping air blast is directed toward the auxiliary spark gap. However, it has been found that extinguishment of the arc at the spark gap is not equally certain under all switching conditions.

It is an object of the invention to provide means to insure extinguishment of the arc at the auxiliary spark gap with equal certainty under all switching conditions.

Another object of the invention is to provide a gas blast circuit breaker with an auxiliary spark gap in series with the main arcing contacts in which one electrode of said spark gap comprises means for throttling the discharge passage through which the pressure blast escapes.

A further object of the invention is to provide a gas blast circuit breaker with arcing contacts and a tubular discharge chamber leading from the arcing contacts in combination with an auxiliary spark gap disposed in said discharge chamber in which the electrode of said spark gap nearest the outlet end of said discharge chamber is formed as an annular disc which throttles the passage leading to said outlet end.

Other objects and advantages of the invention will become apparent upon reference to the following detailed description of the invention in connection with the accompanying drawing, wherein a preferred constructional example of the invention is shown by way of illustration.

In the drawing, Fig. 1 is a central longitudinal section through a circuit breaker embodying the invention, and Fig. 2 is a plan view of the 50 throttling electrode.

While the drawing shows only the circuit breaker per se, it will be understood that the same is connected in the circuit in series with a disconnect switch or the like by means of which

the circuit may be permanently opened after the same is broken and the arc extinguished by the circuit breaker.

Referring more particularly to the drawing, 1 indicates an arcing chamber which is provided with an inlet fitting 2 through which fluid, such as air, under pressure is admitted. The compressed fluid, from a suitable source of supply, such as a storage receptacle or compressed gas generator, is admitted to the pressure chamber 1 under control of a valve, not shown, which may be operated manually or by automatic means responsive to an overload condition of the circuit. The chamber 1, preferably cylindrical in form, may be made of metal, as shown, and is mounted on an insulator 3. If desired, the chamber could itself be formed of insulating material.

The part 4 forming the upper wall of the chamber 1 is formed with an axial opening in which is mounted the fixed contact 5 of the circuit breaker, this contact being in the form of an annular nozzle flaring or widening towards the discharge side thereof.

A movable switch contact 6 coaxial with the nozzle contact 5 is mounted on an axially movable post 7 carried by a piston 8 operating in cylinder 9. The contact 6 is normally resiliently held in engagement with the nozzle contact 5 by a resilient spring 10 acting between the wall 11 of the cylinder 9 and the contact 6, which latter is shaped to close the opening through the nozzle contact.

An arc collector contact 12 is mounted in the discharge chamber 13 axially aligned with the contacts 5 and 6 and spaced therefrom in the direction of discharge of the pressure from chamber 1. This contact 12 serves also as one electrode of an auxiliary spark gap 14. The other electrode 15 of the spark gap, furthest removed from the arcing contacts 5 and 6, is in the form of an annular disc or inverted apertured cup-like member which acts as a throttle, restricting the passage through the discharge chamber 13. The axial aperture 15a in the annular disc 15 acts as a nozzle through which the pressure blast must pass in traveling from the chamber 1 to the atmosphere.

A directing baffle ring 16 having an axial opening and tapering walls directed toward the spark gap 14 is mounted in the discharge chamber 13 for directing the fluid under pressure escaping from the pressure chamber upon opening of the contacts 5 and 6, toward the central aperture 15a of the disc electrode 15.

The disc electrode 15 is connected by means of

an integral arm 17 and bolt 18 to one side of the switch protecting resistance 19, which is preferably made of "Resorbit" in the form of a cylinder carried on the insulating tube 20 which forms the discharge chamber 13. The other side of the resistance 19 is connected by a lead 21 and a brush contact 22 to the movable contact 6, the brush 22 engaging the post 7 which carries said contact.

An exhaust cooler and sound muffler 23 is mounted adjacent the outer end of discharge chamber 13.

The circuit breaker is connected in the circuit serially with the disconnect switch by connecting the binding post 24 of the contact 5 to one terminal of the circuit, and connecting the contact 6 to one side of the disconnect switch, the circuit being completed by connecting the other side of the disconnect switch to the other terminal of the circuit.

In the operation of the circuit breaker when the circuit is to be opened, compressed air or other fluid is admitted to the chamber 1 through inlet 2 by opening of the control valve, before mentioned. Due to the fact that the orifice of nozzle contact 5 is closed by contact 6, pressure will build up in chamber 1 and cylinder 9 and move piston 8 to shift the contact 6 away from contact 5 against the force of spring 10. This causes an arc to be drawn between contacts 5 and 6. The fluid pressure control valve being kept open, a blast of air or other fluid under pressure rushes through the orifice of nozzle contact 5 against the arc from all sides, thereby causing a transfer of the arc established between contacts 5 and 6 from the contact 5 to the auxiliary contact 12. With alternating current, the luminous arc is extinguished during the passage of the arc current through zero. If the rise of current across the arcing contacts on the next half cycle is not very sharp, re-ignition of the arc will not occur since there has been sufficient time for partial deionization of the gas in the arcing chamber. In such event, the circuit breaking operation is completed by opening the disconnect switch, whereupon the fluid pressure valve can be closed. However, if after extinction of the arc as the arc current passes through zero the voltage rise on the next half cycle is very sharp, the spark gap 14 will come into operation to insert the resistance 19 across the arcing contacts, thus damping the voltage rise and lowering the value of the arc current flowing between the contacts 6, 12 and 15 such that the arc may readily be extinguished. The throttling effect of annular disc electrode 15 prevents a rapid drop in pressure in the discharge chamber and the luminous arc across the spark gap 14 between contact 12 and electrode 15 is cooled on all sides and is rapidly deionized by the air escaping through the central aperture 15a due to the building up of the pressure in the discharge chamber on the pressure side of the

disc 15. After extinction of the arc, the disconnect switch is opened and the flow of compressed fluid cut off.

It will readily be seen that means are thus provided for insuring extinction of the arc under all switching conditions.

While a preferred embodiment of the invention has been shown and described by way of illustration, it will be appreciated that various modifications of the details of construction may be resorted to without departing from the spirit of the invention within the scope of the appended claims.

I claim:

1. In a fluid blast circuit breaker including an arcing chamber having a nozzle contact and a pressure operated movable contact cooperating therewith, means for introducing fluid under pressure into said arcing chamber, a discharge chamber leading from said nozzle contact, an auxiliary electrode coaxially of said nozzle contact and electrically connected to the same, means for throttling the passage through said discharge chamber comprising a throttling electrode disposed in said discharge chamber and positioned to form a spark gap with said auxiliary electrode, and a protective resistance connected across said throttling electrode and said movable contact.

2. In a fluid blast circuit breaker including an arcing chamber having a nozzle contact and a pressure operated movable contact cooperating therewith, means for introducing fluid under pressure into said arcing chamber, a discharge chamber leading from said nozzle contact, an auxiliary electrode coaxially of said nozzle contact, a throttling electrode disposed in said discharge chamber beyond said auxiliary electrode in the direction of flow of pressure fluid, said throttling electrode having a nozzle aperture for the passage of the escaping fluid under pressure and positioned to form a spark gap with said auxiliary electrode, and a protective resistance connected across said throttling electrode and said movable contact.

3. In a fluid blast circuit breaker including an arcing chamber having a nozzle contact and a pressure operated movable contact cooperating therewith, means for introducing fluid under pressure into said arcing chamber, a discharge chamber leading from said nozzle contact, an auxiliary electrode coaxially of said nozzle contact, a throttling electrode disposed in said discharge chamber beyond said auxiliary electrode in the direction of flow of pressure fluid, said throttling electrode comprising an annular disc having a restricted central aperture for the passage of escaping fluid under pressure and positioned to form a spark gap with said auxiliary electrode, and a protective resistance connected across said throttling electrode and said movable contact.

HANS THOMMEN.
